Jasper C. Angstead,

UNITED STATES PATENT OFFICE.

ELMER E. MYERS AND JASPER C. ANGSTEAD, OF WATERVILLE, WASHINGTON.

PAINTER'S BUCKET AND BRUSH RETAINER.

1,259,896.

Specification of Letters Patent. Patented Mar. 19, 1918.

Application filed April 24, 1916. Serial No. 93,327.

To all whom it may concern:

Be it known that we, ELMER E. MYERS and JASPER C. ANGSTEAD, citizens of the United States, residing at Waterville, in the county 5 of Douglas and State of Washington, have invented certain new and useful Improvements in Painters' Bucket and Brush Retainers, of which the following is a specification.

10 This invention relates to painters' bucket and brush retainers, the object being to provide a carrier adapted to receive paint buckets, brushes, etc., and to support the same on a ladder.

15 Another object is to equip the carrier with retaining means adapted to embrace the rungs and stiles of the ladder, for supporting the carrier and also for preventing displacement of the same.

20 The above and other objects and advantages of this invention will be in part described, and in part understood from the following description of the present preferred embodiment, the same being illustrated in the accompanying drawings, in which:

Figure 1 is a top plan view of the device constructed in accordance with our invention.

30 Fig. 2 is a front elevational view of the same.

Fig. 3 is a side elevational view of the invention, illustrating the application of the same.

35 Fig. 4 is a front elevational view of the device, illustrating its application, and showing both of the lateral arms thereof engaged with the stiles of the ladder.

Fig. 5 is a similar view, showing only one 40 of the arms engaged with a ladder stile.

In the drawings, in order to illustrate the application of our invention, a ladder 1 is shown which may be of the usual or any desired form.

45 Our improved bucket and brush retainer in this instance comprises a body or carrier 2 which is shown to be of a rectangular configuration, although any desired configuration may be used. The carrier in this instance is shown as made of sheet metal and 50 is equipped with bails or handles 3. The

bails are pivotally engaged to the carrier intermediate the ends of the latter and in proximity to the upper margin thereof. These bails may, when desired, be swung toward the opposite ends of the carrier, as shown in Figs. 3, 4 and 5 to avoid interference of the same with the contents of the carrier, and in order to permit convenient accessibility to the carrier. 60

Rigidly secured to the opposite ends of the carrier 2 are a pair of wire strands 4, which are of an identical configuration. Each strand has one end thereof extended above the upper margin of the carrier 2 and is bent 65 over to provide a hook 5 for engagement with any one of the rungs of the ladder 1. The opposite end 6 of the hook is bent at right angles and secured to the side of the carrier, the terminal thereof being bent laterally 70 to provide an arm 7. The arms 7 are adapted to embrace the ladder stiles, thereby preventing lateral displacement of the carrier on the ladder. As is well known, painters' ladders usually widen toward their lower 75 ends and consequently at some points of the ladder it will be impossible for both arms 7 to embrace both ladder stiles. However, upon reference to Fig. 5 of the drawings, it will be noted that either arm will suffice 80 to retain the carrier from lateral displacement.

It will therefore be seen that the hooks are used to pendently support the carrier 2, while the arms 7 will embrace the ladder 85 stiles in order to prevent displacement of the carrier. In use it will be, of course, understood that the paint buckets are positioned in the carrier 2, the latter also serving as a supporting means for the brushes. 90 The brushes may, if desired, be introduced through the opening 8 in the sides and ends of the carrier.

It will be understood that the above description and accompanying drawings comprehend only the general and preferred embodiment of our invention and that various minor changes in details of construction, proportion and arrangement of parts may be made within the scope of the appended 100 claim without sacrificing any of the advantages of our invention.

We claim:—

A painters' bucket and brush retainer for ladders including a carrier, and wire strands carried by the carrier and secured thereto, one terminal of each strand being formed to provide a hook for engagement with a rung of the ladder to pendently support the carrier, the opposite end of each strand be-

ing formed to provide an arm to engage a ladder stile.

ELMER E. MYERS.
JASPER C. ANGSTEAD.
